FURNITURE LEG

Charles F. Close, Arlington Heights, Ill., assignor to
Arlington Seating Company, Arlington Heights, Ill., a
corporation of Illinois

Application July 25, 1957, Serial No. 47,077

Term of patent 14 years

(Cl. D33—14)

Fig. 1 is a front elevational view of a furniture leg, embodying my new design;

Fig. 2 is a side elevational view thereof;

Fig. 3 is an enlarged sectional view thereof taken along the line 3—3 of Fig. 2;

Fig. 4 is an enlarged sectional view thereof taken along the line 4—4 of Fig. 2;

Fig. 5 is an enlarged sectional view thereof taken along the line 5—5 of Fig. 2; and

Fig. 6 is a rear elevational view of the furniture leg.

The broken line indication of a table top is for illustrative purposes only.

The dominant features of the design reside in the portions shown in full lines on the drawing. The cross members of the furniture legs are substantially the same in cross section as the upright members, the cross sections of which are shown in Figs. 3, 4 and 5.

I claim:

The ornamental design for a furniture leg, as shown and described.
